UNITED STATES PATENT OFFICE

151,220

DESIGN FOR A COSTUMER OR THE LIKE

Lloyd S. Crain, Evanston, Ill.

Application March 29, 1946, Serial No. 128,079

Term of patent 3½ years

(Cl. D33—8)

To all whom it may concern:

Be it known that I, Lloyd S. Crain, a citizen of the United States of America and a resident of Evanston, county of Cook, and State of Illinois, have invented a new, original, and ornamental Design for a Costumer or the like, of which the following is a specification, reference being had to the accompanying drawings, forming a part thereof.

In the drawings:

Fig. 1 is a front view of a costumer showing my new design;

Fig. 2 is a side view of the costumer shown in Fig. 1; and

Fig. 3 is a top plan view thereof.

I claim:

The ornamental design for a costumer or the like, substantially as shown.

LLOYD S. CRAIN.
